US0D1034605S

(12) **United States Design Patent** (10) **Patent No.:** **US D1,034,605 S**
(45) **Date of Patent:** **** Jul. 9, 2024**

(54) **COMPUTING INPUT DEVICE KIT**

(71) Applicant: **Microsoft Corporation**, Redmond, WA (US)

(72) Inventors: **John Helmes**, Limburg (NL); **Aditha May Adams**, Seattle, WA (US); **Simon Cameron Dearsley**, Bellevue, WA (US); **Go Osaki**, Shenzhen (CN); **Hongshan Sun**, Shenzhen (CN)

(73) Assignee: **Microsoft Corporation**, Redmond, WA (US)

(**) Term: **15 Years**

(21) Appl. No.: **29/837,978**

(22) Filed: **May 10, 2022**

(51) LOC (14) Cl. **21-01**

(52) U.S. Cl.

USPC **D14/400**; D21/333

(74) Attorney, Agent, or Firm — Banner & Witcoff, Ltd.

(57) **CLAIM**

The ornamental design for a computing input device kit, as shown and described.

DESCRIPTION

FIG. 1 is a front perspective view of a computing input device kit showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The even length broken lines depict portions of the computing input device kit that form no part of the claimed design. The uneven broken lines represent an unclaimed boundary and form no part of the claimed design.

1 Claim, 8 Drawing Sheets
